Primary Examiner — Darcey E Gottschalk(74) *Attorney, Agent, or Firm* — Knobbe, Martens, Olson & Bear, LLP(57) **CLAIM**

The ornamental design for a bottle, as shown and described.

DESCRIPTION

Fig. 1.1 Front

Fig. 1.2 Bottom

Fig. 1.3 1st Side

Fig. 1.4 Front Perspective

Fig. 1.5 2nd SideFig. 1.6 3rd Side

Fig. 1.7 Top

The dot-dash line seen in 1.2 is a boundary line, it being understood that the claimed design extends up to the boundary line but does not include the boundary line nor anything within the circumference of the boundary line. The evenly broken lines in 1.2 indicate environmental features that form no part of the claimed design.
